ASH RECEPTACLE

Fred G. Julyan, Euclid, and William M. Schweickart, Bay Village, Ohio, assignors to Pocahontas Fuel Company Incorporated, New York, N. Y., a corporation of Virginia

Original application August 3, 1940, Serial No. 350,500. Divided and this application February 21, 1945, Serial No. 579,102

3 Claims. (Cl. 220—33)

1

This invention relates to stokers and particularly to those made for domestic and analogous uses.

The object of the invention is to provide a domestic type stoker which is simple, easy and inexpensive to make and install, which may be readily assembled in a variety of arrangements with a minimum of changes and extra parts so as to accommodate different installation conditions, which is rugged and durable, which is clean and efficient in operation and which requires a minimum of attention.

A further object of the invention is to provide an ash can container adapted to receive and retain ashes under impulse from an underneath feed so as to cleanly and compactly accumulate the ashes for removal and disposal of its contents and replacement of the can ready for refilling.

In the accompanying drawings,

Fig. 1 is a plan view of a stoker embodying the various features of this invention;

Fig. 2 is a side elevation of the stoker shown in Fig. 1;

Fig. 3 is a vertical sectional view of the ash disposal unit of the stoker shown in Fig. 1, taken along the axis of the conveyor as indicated by the line 12—12 in Fig. 1;

Fig. 4 is a vertical sectional view of the ash disposal unit taken transverse to the conveyor as indicated by the line 13—13 in Fig. 3;

Fig. 5 is a plan view of the ash disposal unit taken as indicated by the line 14—14 in Fig. 4, with the ash can removed but its position indicated;

Fig. 6 is a plan view of the ash can alone, with its ash opening closed; and

Fig. 7 is a plan view of the ash output opening in the conveyor pipe.

Referring to Figs. 1 and 2, the complete stoker consists of a burner unit 1, an ash disposal unit 2 and a drive unit 3, as shown, in conjunction with a suitable coal supply or pick-up unit, not shown. The latter preferably consists of a coal collector unit of the type shown and described in William M. Schweickart and Fred G. Julyan Patent No. 2,306,189, issued December 22, 1942, this unit being positioned in the coal bin serving to collect coal and feed it into the bin of the conveyor pipe 4 and is driven from the bin end of the conveyor screw 5.

Conveyor screw 5 operates within a conveyor tube or pipe 4 extending from beneath the burner unit 1 to the coal collector unit. If necessary, the conveyor 4, 5 may include a suitable knuckle, not shown, to enable the coal to be fed from a

2

bin which is at an angle to the portion of the conveyor 4, 5 adjacent the burner unit.

Referring now to Figs. 1, 2, 3, 4, 5 and 6 showing the ash disposal unit 2, this unit includes a substantially circular ash output opening 106 positioned at the top of the conveyor pipe 4, a substantially circular ash output tube 107 communicating with the ash output opening 106 and extending vertically above the same a short distance, and an ash can 108 having a substantially circular opening 109 in its bottom 110, the ash can being positioned with its bottom 110 adjacent the top of the ash output tube 107 with the ash can opening 109 communicating with the top 15 of the ash output tube 107.

The ash can 108 rests upon a table-like support 111 which is secured to the conveyor pipe 4 by the clamp 112. The ash output tube 107 conveniently is an integral part of the ash can support 111, the two parts being joined by an annular portion 113 formed with two pockets 114 at opposite sides of the conveyor pipe 4 through the bottom of which extend the clamping bolts 115 engaging the clamping strap 112.

25 The ash output tube 107 is provided with two shoulders 116 at opposite sides of the conveyor pipe 4 which fit over the adjacent edge of the ash output opening 106. These shoulders insure the proper positioning of the tube 107 over the ash output opening 106. These shoulders taper in thickness, being a maximum thickness at the two lowermost portions w and x of the ash output opening 106 and tapering to extinction over the two uppermost portions y and z of the ash output opening 106 (see Figs. 3, 4 and 7, the latter being a plan view of the opening 106). It is to be noted that the edge of the ash output opening 106 is substantially radial at every point along its circumference, and that the dimension of the opening 106 transverse to the conveyor pipe 4 is nearly equal to the diameter of the pipe, with the result that the edge of the opening 106 at the lowermost portions w and x presents a substantial flange for engagement by shoulders 116 while at the 30 uppermost portions y, z there is no flange for engagement by the shoulders 116.

The ash flight 103 on the conveyor screw 5 terminates short of the center of ash output opening 106 but within the nearest portion z of the edge thereof. The conveyor screw 5 also has a reverse ash flight 117 starting beyond the center of the ash output opening 106 but within the furthest portion y of the edge thereof. The adjacent ends of the ash flight 103 and reverse ash flight 117 are in axial alignment and are joined by a par-

allel bar 118 parallel to the axis of the conveyor screw 5, this bar 118 being secured to the ends of the adjacent flights and to the shaft portion of the conveyor screw. Parallel bar 118 is centered under the ash output opening 106 and extends across a substantial portion thereof.

In operation, the ash disposal unit 2 conveys the ash from under the burner unit 1 to under the ash can 108 by means of the ash flight 103 on the conveyor screw 5. The ash is then forced upwardly through the ash output opening 106 and up through the bottom of the ash can 108 by the action of ash flight 106, reverse ash flight 117 and parallel bar 118 on conveyor screw 5, this upwardly forcing action at the same time desirably altering the physical characteristics of the ash so as to substantially reduce its bulk or, expressed in another fashion, to increase the specific gravity of the ash so that a given bulk weighs substantially more after having passed through the ash disposal unit than it otherwise would. This may be shown by comparing the weight of a given bulk of ash forced up into ash can 108 with the same bulk of ash which may be discharged through an opening in the bottom of the conveyor pipe 4 down into ash cans placed in a suitable recess below the floor level. The ash forced up into the ash can 108 as described weighs about 1.6 to 2 times (and under some circumstances up to nearly 3 times) as much as the same volume of ash discharged into the cans under the floor level.

It is observed, in looking down on top of the ash output opening 106 during operation of the stoker, that the ash wells up through the ash output opening 106 and the ash output tube 107 into the bottom of the ash can 108, and then the ash subsides, the welling up and subsiding occurring alternately and in synchronism with the rotation of the conveyor screw 5. In other words, a complete cycle of welling up and subsiding coincides with one revolution of the parallel ash bar 118 about the axis of conveyor screw 5. The subsidences are less than the welling up of the ash for there is an incremental building up of the ash in the can 108. This occurs until the ash can 108 is full.

It is also observed that the ash which is forced up into ash can 108 through its bottom is much finer than the ash which drops down into the top of the ash can, as described, some of the ash being so fine as to be powdery-like. Generally, the ash is composed of fine particles of free ash and very small particles of granular clinkers not in excess in size of a pea. There may also be a small amount of coke in particles not exceeding one-half inch in size.

Apparently the upward forcing of the ash into the ash can through its bottom is accompanied by a disintegration of the ash into finer particles and elimination of the air spaces in the ash itself, this disintegration apparently being due to the pressures to which the ash is subjected in the region of the ash output opening 106.

It is to be noted that this upward forcing of the ash into the ash can through its bottom automatically provides a seal of ash preventing the leakage of air from the furnace room and the top of the ash can 108 into ash chamber 46 of the burner unit 1. Thus, although the ash in the conveyor pipe 4 in the region of the burner unit 1 does not fill the pipe, and although the ash can 108 may be empty or nearly so, the conveyor pipe 4 in the region of the ash output opening 106 is completely filled with ash, with

much of this ash closely compacted. As a result air cannot pass from the ash can 108 down through the opening 106 into the top portion of conveyor pipe 4 and thence up into the ash chamber 46. As any air which leaks into ash chamber 46 affects the combustion of the fuel above grate 47 and counteracts the control over this combustion afforded by the air passing from the air tube 14 through the tuyère openings 31, this air seal action of the ash disposal unit 2 is particularly desirable.

The ash can 108 is provided with a sliding gate 121 at its bottom for closing the ash can opening 109 to prevent the ash from leaking out of the can during and after its removal from the ash can support 111. This gate is secured to a vertical gate shaft 122, as by welding, and the lower end of shaft 122 is rotatably secured to the ash can bottom 110, as by passing through an opening therein and having a washer welded to the gate shaft below the can bottom. The gate shaft 122 extends up to the top of the can, where it passes through an opening in cross member 123 which is secured to the tops of the two long sides 124 of the can. Just above this cross member 123 the gate shaft 122 is provided with a handle 125 transverse to the shaft 122. The bottom 110 of the can is provided with gate stops 126 for the open and closed positions of the gate and the front edge of the gate is preferably ground to a sharp edge to facilitate the closure of the gate when the can is full of ashes.

The ash can 108 is rectangular in plan view, with the cross member 123 and gate shaft 122 at the midpoint between the ends of the long sides 124. Cross member 123 thus serves as a handle for lifting the ash can, and gate operating handle 125 is aligned with this cross member 123 when the gate is closed so that the two handles are included within the grasp of the hand of the person lifting and removing the ash can, with the result that the ash can gate is not accidentally moved from closed position during removal of the can.

The ash can 108 is held in position on the ash can support 111 by the guide walls 127 thereon extending around the two long and one of the two short sides thereof. The bottom 108 of the ash can extends a short distance outwardly beyond the short side 128 of the can nearest the opening 109 therein, this extension forming a flange 129. A portion of the guide wall 127 engaged by this flange 129 is provided within a lip 130 extending over the top of the flange 129 so as to prevent tipping of the can. In this connection it is to be noted that the can extends over beyond the short side of the ash table support which does not have a guide wall 127.

In removing a full ash can 108 from its support 111 the gate operating handle 125 is first rotated so as to cause the gate 121 to close the ash can opening 109, then the can is raised slightly and pivoted about the lip 130 so as to raise the edge of the ash can opening 109 above the top of ash output tube 107, and then the can is moved transversely to the conveyor pipe 4 sufficiently to move the ash can flange 129 from under the lip 130. The ash can may now be removed and laid aside for emptying and an empty ash can put back in place of the full one.

One end of gate operating handle 125 preferably extends beyond one side 124 of the ash can when the handle is in gate-closed position (see Fig. 6). A cover (not shown) is provided which

fits over the ash can when the latter is in place on the support 111. This projecting end of handle 125 prevents the replacement of this cover over the can when the ash can gate is in closed position. Thus, this serves to insure the opening of the ash can gate after an empty can is put in place.

The conveyor pipe 4 is provided with an ash return opening 131 at the top smaller than the ash output opening 106 and beyond the same so that the ash return opening 131 is above the reverse ash flight 117. A spout 132 formed on the ash can support 111 fits into the ash return opening 131, this spout communicating with the annular portion 133 of the ash can support 111. That part of this annular portion 113 which is not formed into pockets 114 is formed into a canal around the ash output tube 107 to collect any ash that may spill over the top of the tube 107, as when a can is removed while the stoker, and thus conveyor screw 5, is in operation. When the ash in this canal rises to the level of the ash can support 111, the ash in the canal may be pushed around to the spout 132 so that it drops down through the ash return opening 131 into the conveyor pipe 4. The reverse ash flight 117 then moves this ash over into the mass of ash under ash output opening 106, where it joins the ash being moved up into the ash can.

Preferably the parallel bar 118, the reverse ash flight 117 and a corresponding length of ash flight 103 are separable from the remainder of the conveyor screw 5 so as to form a removable ash tip portion for the conveyor screw. This is conveniently effected by mounting these parts on a sleeve 134 which fits over the tubular shaft portion 135 of conveyor screw 5 and is secured thereto by the bolts 136. This ash tip portion may then be readily specially treated to withstand the wear to which it is subjected and may also be replaced, if necessary, without replacing the entire conveyor screw 5.

The specific ash container 108 shown in the drawings is 13" high, 15" long and 9" wide, the opening at the bottom being 3 $\frac{3}{8}$ " in diameter. This corresponds to a capacity of the order of 1 cubic foot with a horizontal cross section of 1 square foot, the bottom opening being spaced from the side walls and having its longest dimension less than half the minimum distance between the inner side surfaces of said walls. This leaves a ledge around the opening, the minimum dimension of which is greater than half the longest dimension of said opening.

The size of ash can 108 may be increased in length and width, if desired, without impairing the operation of the ash disposal unit. The height of ash can 108 is preferably not materially increased from the height stated when the ash disposal unit is constructed as shown, for as the ash can height is increased there develops a tendency for the can to be pushed upwardly after the ash has reached a certain height.

The ash disposal unit 2 is simple, easy and inexpensive to make and install and provides a means of disposing of the ashes which is clean, rugged and requires attention very infrequently. Materially contributing to the infrequent attention is the fact that the ashes are substantially reduced in bulk by the ash disposal unit, so that it requires a relatively long time to fill the ash can.

This application is a division of application Serial No. 350,500, filed August 3, 1940, now

Letters Patent No. 2,370,246, of February 27, 1945.

We claim:

1. A container of the class described adapted to be positioned adjacent a supply outlet through which granular material is intermittently forced upward comprising a portable can having surrounding vertically extending inner side surfaces for retention of material and a bottom extending inward from said side surfaces in all directions and having an opening adapted to receive granular material upward from below through said outlet, said opening having its longest dimension less than half the minimum distance between said inner side surfaces and spaced from all of said surfaces to leave the surrounding portion of said bottom as a ledge retaining successive increments of the said material intermittently passing upward through said opening, and a gate slidably mounted on the bottom of the can to open and close the bottom opening therein and with an operating handle positioned at the top of the can and connected to the gate and adapted to move the same to closed position when the can is full of material, and a transverse handle member extending across the top of the can parallel to said operating handle in closed position thereof so that both the operating handle and the handle member may be grasped together by the hand of the user.

2. A container of the class described adapted to be positioned adjacent a supply outlet through which granular material is intermittently forced upward comprising a portable can having surrounding vertically extending inner side surfaces for retention of material and a bottom extending inward from said side surfaces in all directions and having an opening adapted to receive granular material upward from below through said outlet, said opening having its longest dimension less than half the minimum distance between said inner side surfaces and spaced from all of said surfaces to leave the surrounding portion of said bottom as a ledge retaining successive increments of the said material intermittently passing upward through said opening, and a gate slidably mounted on the bottom of the can to open and close the bottom opening therein and with an operating handle positioned at the top of the can and connected to the gate and adapted to move the same to closed position when the can is full of material, and a transverse handle member extending across the top of the can parallel to said operating handle in closed position thereof so that both the operating handle and the handle member may be grasped together by the hand of the user, said operating handle having one end extending beyond the side of the can in closed position of the gate so as to require the gate to be opened before positioning of a cover on the can.

3. A container of the class described having a capacity of the order of one cubic foot and of the order of one square foot in horizontal cross section and adapted to be positioned adjacent a supply outlet through which granular material is intermittently forced upward comprising a structure having surrounding vertically extending inner side surfaces for retention of material as it is fed upward through said supply and a bottom extending inward from said side surfaces in all directions and having an opening adapted to receive said granular material upward from below through said outlet, said opening having its longest dimension less than half the minimum dis-

tance between said inner side surfaces and spaced from all of said side surfaces a distance greater than half said longest dimension to leave the surrounding portion of said bottom as a ledge extending entirely around said opening and retaining above said opening a mass of said granular material formed by successive increments thereof of intermittently passing upward through said opening, and a single sharp edged gate slidably mounted on the upper surface of the said bottom of the container structure and clear of the edges of the opening therein in open position of the gate and closely fitting over all of said edges of the opening in closed position of the gate to open and close over said entire bottom opening, said gate being entirely within the sides of said container in both open and close positions and with an operating handle positioned at the top of the can and connected to the gate and adapted to slide the same over the upper edges of said opening to closed position when the can is full of material.
